UNITED STATES PATENT OFFICE.

JULIAN O. ELLINGER, OF NEW YORK, N.Y.

REINFORCEMENT FOR CONCRETE CONSTRUCTION.

No. 890,035.

Specification of Letters Patent.

Patented June 9, 1908.

Application filed May 14, 1907. Serial No. 373,633.

To all whom it may concern:

Be it known that I, JULIAN O. ELLINGER, a citizen of the United States, and a resident of the city, county, and State of New York, have invented certain new and useful Improvements in Reinforcement for Concrete Construction, of which the following is a specification.

This invention relates to improvements in reinforcements for building construction and especially for beams, girders and the like, which have their body portion composed of plastic material, preferably concrete. The objects of the invention will hereafter appear from the description of the invention: but it may be here stated that one of the leading features of the present invention consists in providing a reinforcing girder for concrete, or other cementitious or plastic substance, herein intended to be included within the term "concrete"), wherein there are longitudinally extending rods or bars, forming tension members, and a shear member composed of a fixedly united system of longitudinal and transverse rods which are arched between the tension members and are fixedly secured to the latter. For fixedly securing the longitudinal and transverse rods of the shear member together, they are preferably electrically welded at their places of intersection. Such a construction forms a unit reinforcing girder which may be produced at a minimum expense, and one in which strain imposed on any part of the shear member is transmitted throughout the series of longitudinal and transverse bars of the network, and also to the tension members, thus making the entire network effective to support strain imposed on any part thereof and to transmit the same to the tension members. In practice, and as herein shown, these girders are spaced apart and they are connected with each other by a second netting which is embedded in the concrete of the floor supported by the beams or girders, and into which concrete of the floor the reinforcing girders extend. This second netting is similarly formed of longitudinal and transverse rods or arms fixedly united with each other, as by electric welding, at their places of intersection, and it is positively secured to the reinforcing girders referred to, so as to transmit strains thereto.

The invention is illustrated in the accompanying drawings, which form part of this application, and in the several views of

which the same reference character indicates the same part.

Referring to the drawings, Figure 1 is a side view of a beam or girder made according to my invention. Fig. 2 is a cross section thereof on line 2 of Fig. 1. Fig. 3 is a cross section of a slight modification. Fig. 4 is a section showing part of a floor made according to my invention. Fig. 5 is a plan view of the reinforcement shown in Fig. 4. Fig. 6 is a cross section showing a slight modification of the arrangement of the side beams. Fig. 7 is a side view of a modified construction of a side beam. Fig. 8 is a side view of another modification. Fig. 9 is a detail view of a modified arrangement of tension rods or bars. Fig. 10 is a cross section on the line 10 of Fig. 8.

The part marked A on the drawing represents a pair of side members each of which consists of a pair of rods a, a' arranged vertically over each other and connected together by a vertical web a''. The upper rod a' of each of these side members is sheared from the web a'' at each end a predetermined distance, and these separated ends are bent upwardly to form the divergent inclined portion of said members. Connected to these side members is the shear member. This is formed of a network of longitudinal rods b and transverse rods b'. These rods are connected together, preferably by electric welding, at their points of intersection b and form a net or mesh. This mesh is adapted to be bent to form a connected series of loops or stirrups of approximately U shape. They may be formed, however, in any other desirable shape. The ends of these transverse or vertical rods b' are bent around the bar a of the side member, and are connected to the lower rod a or to the web a'', or both, in any suitable way, but preferably by electric welding.

The side members and the shear members constructed as described, form a unit reinforcing girder for reinforcing concrete girders. Connected to the side members and preferably resting on and welded to the upper edge of the web a'' are the centering members C. These members are so placed, as shown, that the lower ends c thereof will rest upon the bottom of the form, not shown, in which the concrete is placed, and the sides c' thereof will rest against the inner side of said form, accurately centering the unit bar in the form into which the concrete is poured.

The centering members C may be put in place when the unit bar is constructed, or

they may be put in place and welded to the unit bar just before the bar is placed in the concrete mold. In using these unit girders the forms are located at a certain distance apart and the unit girder is placed therein. On the top of each of these girders or the shear members, I lay the netting D, which consists of longitudinal rods *d* and transverse rods *d'*, which are preferably welded together at their places of intersection *d* to form the netting, as shown in Fig. 5. This netting between the bars is slack or curved, and it is positively connected to the loops or stirrups. In the form herein shown it rests on the upper longitudinal bars *b* of the shear member and is attached to the shear member by passing the rods *E* underneath the vertical rods *b'* of the shear member and over the rods *d* of the netting, as shown in Figs. 4 and 5 of the drawing, these rods *E* securely fastening the netting to the unit bar, or rather, to the shear members thereof, it being understood that the proper form of frame work is constructed and the concrete F is placed therein to make such a construction, as shown in Fig. 4, when the form is removed.

In Fig. 3 I have shown a slight modification of the side member A. This construction which I have marked A' consists of an eye beam, the upper flange of which is cut away at the ends from the web *a*² and bent up to form the upper inclined portion *a*³ of said member.

In the construction shown in Figs. 1 to 5 and Fig. 7 of the drawings, I have placed the inclined portion *a'* or *a*³ of the side members outside of the shear member. It is to be understood that I am not confined to this arrangement, and in Fig. 6 I have shown a construction in which the inclined portions *a'* of said member are so arranged that they lie inside the vertical rods or bars *b'*, forming the shear member. The lower ends of these rods *b'* are turned around the rod *a* in such a manner that the end thereof will rest against the inner surface of the web *a*² instead of the outer surface, as shown in the prior figures of the drawing.

Instead of bending the free ends of the stirrups around the lower bars of the side members, I may connect the stirrups to the side members by securing the free ends of the stirrups directly to the web of said side members, as shown by Fig. 7 of the drawing. The stirrups may be secured to the web by electric welding, riveting or in any other suitable manner.

In Fig. 7 I have also shown a modified construction of centering device. As there shown, the centering device consists of a number of plates C of metal, secured to the flanges of the side members. Each of these plates is split and one leg C² of each is extended downwardly to form the bottom centering device, and the other leg C¹ of each

plate is extended laterally to form the other centering member.

In some cases it may be advisable to bring the stirrups and the upper bent portions of the side members in contact, as shown in Figs. 6 and 7, and these stirrups may be secured to the side portions of the side members by electric welding or otherwise, at places of contact, z. This is an especially desirable form for the reason that, in conjunction with the uniting of the other parts of the structure already described, it joins the entire structure into one unitary whole, so that strains on any part thereof is transmitted to other parts, throughout the whole. The arrangement of the netting outside of the side members, shown in Fig. 6, also has peculiar advantages but this is not claimed as it is better developed in the structure shown, and is claimed, in my copending application No. 382,155 filed July 5, 1907.

In Fig. 8 I have shown a modified construction of the side members. In this construction I have used two rods *a* and *a'* arranged vertically over each other. The end of the upper rod is bent on an incline, as shown in Fig. 1 of the drawing. Instead of connecting these rods together by a web I may connect them together by a series of clips F secured to the rods at their unbent or parallel portions.

In Fig. 9 I have shown a side member formed with the rods *a* and *a'* parallel throughout and the series of clips extending to the ends of the bars.

It is understood that in the constructions shown in Figs. 8 and 9 the clips are spaced a predetermined distance, and they are so constructed that the bars *a*, *a'* are separated, one lying over the other.

From the foregoing description the advantages of the invention will be readily understood. While I have shown certain forms of construction, it is to be understood that many changes may be made therein and many apparently widely different embodiments of the invention may be made without departing from the spirit of the invention, and for this reason the constructions must be interpreted as illustrative and not in a limiting sense.

It is also to be understood that the language used in the following claims is intended to cover all the generic and specific features of the invention and all statements or matter relating to or bearing upon the scope of the invention, which, as a matter of language, might be said to fall therebetween.

Having now described my invention, what I claim as new and desire to secure by Letters Patent is:

1. In a reinforcing means for concrete construction, a reinforcing girder comprising longitudinal rods or bars or tension members, and a shear member, said shear member com-

posed of a network of longitudinal and transverse rods or arms fixedly united to each other at their places of intersection, said network arched between the tension members 5 and suitably secured thereto.

2. In a reinforcement for concrete construction, a plurality of spaced reinforcing girders, each comprising longitudinal rods or bars or tension members and a network composed of a connected series of rods or arms 10 bent into arch form between the tension members and suitably secured thereto, said network having its elements fixedly united with each other at their places of intersection, 15 and a second netting extending from one reinforcing girder to another and fixedly connected thereto and having its elements fixedly united to each other at the places of intersection.

20 3. A reinforcement for concrete construction consisting of a plurality of spaced reinforcing girders, each having a series of arched rods or arms, and tension members to which the same are secured, longitudinally extending rods or arms connecting the arch rods, a netting 25 extending from one to another between the arched rods, resting on the longitudinal rods, and additional rods or arms at the junctions of the arched rods and netting, 30 for attaching the same to each other.

4. In a reinforcement for concrete construction, a plurality of spaced reinforcing girders each comprising longitudinal rods or bars forming tension members, and a network 35 composed of a series of rods or arms bent into arch forms between the tension members and provided with a longitudinal connecting rod or arm which is fixedly united to the other rods of the network at the places 40 of intersection, a second netting extending from one girder to another and resting on said longitudinal rods, and additional rods or arms at the junction of the arched rods and netting, for attaching the same to each 45 other.

5. A reinforcement for concrete construction, consisting of a series of spaced girders, said girders being formed of a pair of side members and a shear member consisting of a series of vertical loops formed of bent rods or 50 arms and longitudinally extending rods or arms connecting the same with each other, said bent rods having their ends secured to the side members, a netting or mesh extending from one girder to the other and formed

of a series of longitudinal rods or arms and a series of transverse rods or arms welded together, said netting resting upon said longitudinal rods, and rods or arms extending under the loops and over the rods of the 60 mesh to secure the said mesh to the girders.

6. A reinforcement for concrete construction, comprising two side members each formed of a pair of longitudinal rods or bars one over the other, the ends of the upper rods 65 being bent or upturned, the unbent portions being connected to the lower rods, a series of stirrups, consisting of bent vertical rods or arms, the free ends of which are extended around and secured to the lower rods of the 70 side members, and a series of longitudinal connecting rods or arms fixedly united to the stirrups at the places of intersection.

7. A reinforcement for concrete construction, comprising two side members each 75 formed of a pair of longitudinal rods or bars one over the other, the ends of the upper rods being bent or upturned, the unbent portions being connected to the lower rods, a series of stirrups consisting of bent vertical rods or 80 arms, the free ends of which are extended around and secured to the lower rods of the side members, and a series of longitudinal connecting rods or arms fixedly united to the stirrups at the places of intersection, and centering devices, one of which is adapted to rest upon the bottom of the mold and the other to rest upon the inner side of the mold. 85

8. A reinforcement for concrete construction, comprising two side members, each 90 formed of a pair of longitudinal rods or bars one of the same lying in a plane over the other, the ends of the upper rods being bent or upturned, and a network composed of a connected series of rods or arms bent into 95 arch form between the side members and suitably secured to the lower rods of the pair, said network having its elements fixedly united with each other at their places of intersection, and said network being fixedly 100 united to the upturned ends of the upper rods of the side members.

In witness whereof I have hereunto set my hand at the city, county and State of New York, this 7th day of May, 1907.

JULIAN O. ELLINGER.

In presence of—

EVARTS TRACY,
RICHARD D. EVANS.
